UNITED STATES PATENT OFFICE.

CLIFTON B. CORELL, OF NEW YORK, N. Y., ASSIGNOR TO UNDERWOOD COMPUTING MACHINE COMPANY, OF NEW YORK, N. Y., A CORPORATION OF NEW YORK.

TYPEWRITING MACHINE.

Application filed March 25, 1918. Serial No. 224,428.

To all whom it may concern:

Be it known that I, CLIFTON B. CORELL, a citizen of the United States, residing in New York city, in the county of New York 5 and State of New York, have invented certain new and useful Improvements in Typewriting Machines, of which the following is a specification.

My invention relates to typewriting machines, and more especially to margin-stops which limit the travel of the typewriter carriage.

The invention is herein disclosed as applied to the right-hand margin-stop of an 15 Underwood addendagraph or master wheel typewriting and adding machine. This is the margin-stop which limits the travel of the carriage as the carriage is returned to the right, for the purpose of beginning a 20 new line.

The margin-stops for a typewriting machine must withstand severe blows, such as may be given when the typewriter carriage is arrested unexpectedly, and at the same 25 time the margin-stops must be settable in as convenient a manner as possible, so that the attention of the typist will be diverted to the smallest possible amount in setting such stops. In other words, the finger 30 movements in setting such stops must be natural, or else easily learned, and of such a nature that, when learned, they are easily carried out. With these and other objects in view, the margin-stop herein disclosed 35 is provided with a single handle, which serves both for shifting it and for releasing it, and said handle stands in the neighborhood of the usual Underwood typewriter carriage scale-plate, with the result that, 40 when the typist's hand is adjusting the stop at a given letter-space on said scale, the hand, and especially the fingers which were adjusting the stop, will be in full view of the eye which is looking at the 45 pointer on the scale-plate.

The margin-stop of the present invention is especially adapted to be used in machines of the type of the Underwood addendagraph referred to above, in which 50 there is a track fixed in front of and somewhat above the usual typewriter scale-plate, along which track the plate slides which carries the totalizer. The present margin-stop enables the typist to readily grasp and

adjust the margin-stop while looking over 55 the track at the scale-plate.

Other features and advantages will hereinafter appear.

In the accompanying drawings,

Figure 1 is a plan view, partly broken 60 away, of part of an Underwood typewriting machine, showing my invention as applied thereto.

Figure 2 is a section through the margin-stop viewed from above. 65

Figure 3 is an end view of the parts seen in Figure 1.

Figure 4 is a fragmentary perspective of many of the parts seen in Figure 1, viewed from almost behind the machine. 70

The usual Underwood addendagraph typewriting machine carriage is provided with a pointer 10, which overlies the scale-plate 11 on the frame of the typewriter, said scale-plate being graduated at letter-space intervals, to correspond to the letter-feeding movements of the carriage. When it is desired to return the typewriter carriage to the right, to begin a new line, the typist seizes the usual line-space handle (not shown) and swings it to the right, thereby carrying along the carriage to the right until a lug 12 on the carriage strikes a lug 13 on the right-hand margin-stop 14 which arrests the carriage. The margin-stop in the usual Underwood typewriting machine and addendagraph 75 is carried on a slide-bar 15 and a rack-bar 16, both concealed beneath the usual front bar 17 on the typewriter frame, on which latter bar the scale-plate 11 is mounted. In front 90 of and slightly above the scale-plate 11 is a transverse bar or plate 18 of the addendagraph comprising tracks 19, on which the totalizer carrying-plate 20 is adapted to travel. The plate 18 is supported on brackets 21 at the ends of the typewriter, thus leaving the front of the machine open below the plate 18. In order to cause the totalizer-mounting plate 20 to travel with the typewriter carriage, it is connected thereto by 95 arms 22 springing from the posts 23 at each end of the typewriter carriage, and extending forwardly therefrom to the top of the plate 20, thus clearing the scale-plate 11 and other mechanism. The margin-stop 14 comprises a body 24 encircling the bar 15 and an extension 25 thereof partly encircling a considerable length of the rack-bar 16.

100

105

Pivoted on the body 24 on a vertical pin 26, is a rearwardly-extending toothed member 27, comprising teeth 28 adapted to engage with the teeth 29 on the rack-bar 16, and thereby hold the margin-stop-bar in position. Both sets of these teeth are usually provided with one slanting and one nearly vertical face, so that the vertical face will receive the impact of arresting the carriage.

10 Since the rack-bar 16 is usually positioned above, as well as to the rear of the bar 15, the toothed member 27 of the stop is provided with a horizontal portion 30, carrying the teeth which engage the rack-bar, and a 15 lower portion 31, offset both vertically and horizontally, by which it is pivoted to the stop body.

In order to enable the toothed member 27 to be swung into and out of engagement with 20 the rack bar, the stop is provided with a looped handle 32, forming an extension of a sleeve 33, said sleeve being rotatable on the barrel-like extension 34 of the body of the stop which embraces the round bar 15.

25 To cause the handle 32 to swing the toothed member 27 the sleeve 33 is provided with a boss 35 comprising a double cam 36 adapted to engage a pin 37 on the toothed member 27, and positively shift said toothed member 30 27 away from the rack-bar 16 against the tension of the spring 36^a, which acts on the toothed member adjacent its pin 26. In effecting this motion, the handle 32, which normally stands projecting upwardly, adjacent to the scale-plate, and a few letter-spaces to one side of the letter-space at which the pointer of the typewriter carriage will stand when the carriage is arrested, is pressed rearwardly. The typist may then 40 slide the stop until it is at the desired position, as shown by its pointer 10 which overlies the scale-plate 11, and is in the form of a thin plate fast to and projecting from the body of the stop. When the handle 32 is 45 released, it and the toothed member are returned by the spring 36^a. The sleeve 33, of which the handle forms a part, is limited in its rotation by a pin 39 which projects from the sleeve within a slot 40 cut in the 50 barrel 34 on which the sleeve is journaled.

The lug 12 on the carriage, by which the carriage is arrested, may be of the usual Underwood typewriting machine form, in which it is the turned-over end of a lever 41 55 pivoted upon the carriage between its ends and provided with a finger-piece 42 by which one end may be depressed, so that the lug on the opposite end will be lifted clear of the lug 13 on the stop. In order to permit 60 the carriage to pass the stop in letter-feeding direction, the leading edge of each lug is beveled to form a cam, which is adapted to strike a corresponding bevel on the margin-stop-lug, so that the lever will be cammed 65 upwardly against the tension of a spring

(not shown), which normally holds it in its effective position.

The structure described above, permits the handle 32, curving up and over the scale-plate 11, to be easily accessible over the top of the plate 18, and to control the stop, of which the effective portion is behind and below the front bar 17. The lug 13 is firmly held since the lug 13 is close to the rack-bar 16, and the length of the extension 25 along the 75 rack-bar holds the extension steady.

Variations may be resorted to within the scope of the invention, and portions of the improvements may be used without others.

Having thus described my invention, I 80 claim:

1. In a typewriting machine, the combination with a traveling carriage, of a stop comprising a body, a rack bar, an arm swingable on said body into and out of engagement 85 with said rack bar, a handle rotatable on said body transversely to said rack bar, and means including a double-action cam member fast to said handle to swing said arm into and out of engagement with said rack bar. 90

2. In a typewriting machine, the combination with a traveling carriage, of a stop comprising a body, stop-supporting means, comprising a rack bar and a rod on which said body slides, an arm pivoted on said body adapted to be swung into and out of engagement with said rack bar, a handle mounted on said body and rotatable around said rod, and means, including a double cam fast to said handle, to positively swing said 100 arm into and out of engagement with said rack bar.

3. In a typewriting machine, the combination with a traveling carriage, of a stop for said carriage comprising a body, a stop-supporting means including a rack bar, an arm pivoted on said body adapted to engage said rack bar to hold the stop, a scale-plate along which said body is slid able, a handle rotatable on said body near said scale-plate and 105 transversely of said rack bar, and a cam member operated by said handle to swing said arm into and out of engagement with said rack bar. 110

4. In a typewriting machine, for the purpose specified, the combination with a traveling carriage, of a stop for said carriage, a scale-carrying bar as set forth, supporting means for said stop, including a rack-bar beneath said scale-bar, said stop being slid able along said rack-bar, a handle for said stop projecting upwardly as set forth, a toothed member pivoted on said stop to swing to and from said rack-bar, in a plane in which lies the axis of said rack-bar, a pin on said member, and a cam-member secured to said handle effective on said pin to swing said toothed member into and out of effective position. 115 120 125

5. In a typewriting machine, for the pur- 130

- pose specified, the combination with a traveling carriage, of a stop for said carriage, a scale-carrying bar, a rack-bar beneath said scale-carrying bar, a rod, an extension of 5 said stop embracing said rod, so that the stop is slidable along the rod and rack-bar, a handle journaled to rotate around said rod, and connected with said stop to move therewith along said rack-bar and rod, said handle 10 projecting upwardly as set forth, a toothed member pivoted on said stop to swing to and from said rack-bar, in a plane in which lies the axis of said rack-bar, a pin on said member, and a cam-member fixedly 15 connected to said handle effective on said pin to swing said toothed member into and out of effective position.
6. In a typewriting machine, the combination with a traveling carriage, of a stop comprising 20 a body, stop-supporting means, including a rack bar and a rod on which said body slides, an arm pivoted on said body to be swung, in a plane in which lies the axis of said rack-bar, into and out of engagement 25 with said rack bar, a handle mounted on said body and rotatable around said rod, means, including a cam member fast to said handle, to swing said arm out of engagement with said rack bar, and a spring normally 30 holding it in engagement with said rack bar.
7. In a typewriting machine, the combination with a traveling carriage, of a stop for said carriage, a scale-carrying bar, a rack bar beneath said scale bar, a stop slidable along said rack bar, a handle for said stop projecting substantially above said scale-carrying bar, a toothed member swingable on said stop to and from said rack bar, a pin on said member, a cam member secured to said handle effective on said pin to swing 40 said toothed member into and out of effective position, a pin on said handle, and a slot in the body of the stop in which the pin works, adapted to limit the throw of the handle. 45
8. In a typewriting machine, the combination with a traveling carriage, of a stop for said carriage having a long body, a rack bar embraced by said body, a toothed member pivoted on said stop adapted to be swung 50 into and out of engagement with said rack bar, a rod, a barrel forming part of said stop embracing said rod to steady the stop, a sleeve on said barrel, a cam member fixed to said sleeve, a pin on said toothed member engaging said cam member, and a handle fast to said sleeve for swinging the cam member to operate the pin. 55
